(57) **CLAIM**

The ornamental design for a bottle, as shown and described.

DESCRIPTION

FIG. 1 is a top, right, front perspective view of a bottle embodying our new design;

FIG. 2 is a front elevational view thereof, the rear elevational view being identical to the front elevational view;

FIG. 3 is a right side elevational view thereof, the left side elevational view being identical to the right side elevational view;

FIG. 4 is a top plan view thereof; and,

FIG. 5 is a bottom plan view thereof.

The broken line representations in the views show unclaimed subject matter only and form no part of the claimed design.

1 Claim, 4 Drawing Sheets

FIG. 1

FIG. 2

FIG. 3

FIG. 4

FIG. 5
